CLAIM

The ornamental design for a teeth flossing wedge with handle, as shown and described.

DESCRIPTION

FIG. 1 is a perspective view of a teeth flossing wedge with handle showing my new design;

FIG. 2 is a perspective view of the teeth flossing wedge with handle shown in an environment of use;

FIG. 3 is a front view of the teeth flossing wedge with handle;

FIG. 4 is a back side view thereof;

FIG. 5 is a left side view thereof;

FIG. 6 is a right view thereof;

FIG. 7 is a top view thereof; and,

FIG. 8 is a bottom view thereof.

The broken lines in FIG. 2 depict environmental structures of a human face, mouth, teeth and hand that form no part of the claimed design.

1 Claim, 5 Drawing Sheets(56)
